UNITED STATES PATENT OFFICE.

GEORGE WILLIAM BAYLEY, OF BROOKLYN, NEW YORK.

DESIGN FOR A LAMP.

SPECIFICATION forming part of Design No. 20,053, dated July 22, 1890.

Application filed June 28, 1890. Serial No. 357,153. Term of patent 7 years.

To all whom it may concern:

Be it known that I, GEORGE WILLIAM BAYLEY, of Brooklyn, in the county of Kings and State of New York, have invented and produced a new and original Design for Lamps, of which the following is a specification, reference being had to the accompanying drawing, forming a part thereof, and representing in perspective elevation a lamp embodying my design.

The leading feature of my design consists in the reservoir of the lamp, having the form and configuration of a base-ball, and the support for the reservoir, having the form of a tripod, the three members of which have the form and configuration of base-ball bats.

A designates the reservoir, having the external configuration of a base-ball. B B designate the three members of the tripod, representing base-ball bats united at α , having the ball A arranged between them above their point of union α , and represented as having their lower ends supported on a circular base C, on the upper face of which is a figure b, representing the diamond of a base-ball field.

What I claim as my design is—

The design for a lamp herein shown and described.

GEORGE WILLIAM BAYLEY.
